UNITED STATES PATENT OFFICE.

HENRY A. CONSTANTINE, OF NIAGARA FALLS, NEW YORK.

WET-MACHINE.

1,380,637.

Specification of Letters Patent. Patented June 7, 1921.

Application filed January 31, 1919. Serial No. 274,332.

To all whom it may concern:

Be it known that I, HENRY A. CONSTANTINE, a citizen of the United States of America, residing at Niagara Falls, in the county of Niagara and State of New York, have invented certain new and useful Improvements in Wet-Machines, of which the following is a full, clear, and exact description.

10 My invention relates generally to wet machines, and more particularly to automatic means for removing the sheets of pulp from said machines and laying the said sheets in a pile.

15 It is well known to those skilled in the art, that in machines of this type the pulp is conducted to the pressure rolls of the machine by means of an endless sheet or belt of fabric, preferably felt; and the pulp so conducted is continuously deposited upon one of the pressure rolls until the sheet of pulp on this roll has reached a predetermined thickness. At this time the sheet of pulp is slit lengthwise of the roll and there-20 by removed from the machine. This slit-25 ing operation is usually performed by an operator who uses a stick or a knife to slit the sheet of pulp. After the sheet has been discharged from the machine the operator 30 usually folds the sheet and places the same in piles.

As the length of time required for the slitting and folding operation is but a small fractional part of the time it takes for the 35 sheet of pulp to reach its predetermined thickness, it will be seen that a good deal of time is lost by this manual method of performing these operations, as it is necessary for the operator to remain at the machine 40 and wait until the sheet of pulp is ready to be slit.

The principal object of my invention has been to provide a device which will automatically slit the sheet of pulp when it has 45 reached the predetermined thickness, and while the machine is in operation.

Another object has been to provide a device for slitting the sheet of pulp which shall perform the operation as nearly like 50 that performed by hand as is mechanically possible.

Another general object has been to provide means for grasping one edge of the sheet; moving the sheet away from the machine as it is being discharged therefrom; 55 releasing the sheet at a predetermined point,

and allowing it to fall and to be deposited in a pile.

Another object has been to provide a device of this nature which may be easily attached to existing machines.

Furthermore, my device is simple in its operation and of such a design that it will not easily get out of order.

The above objects and advantages, as well as others which will be apparent to those skilled in the art, have been accomplished by the device shown in the accompanying drawings, which form a part of this application. In the drawings:

Figure 1 is a front elevation of my device with portions thereof broken away.

Fig. 2 is a side elevation of my device.

Fig. 3 is an enlarged, plan view of the cutter of my device and its associated parts.

Fig. 4 is a fragmentary, front view, slightly enlarged, of the cutter operating means.

Fig. 5 is an enlarged, fragmentary, sectional plan view of the cutter operating means, taken on line 5—5 of Fig. 1.

Fig. 6 is an enlarged fragmentary sectional view of the same means, taken on line 6—6 of Fig. 1.

Fig. 7 is an enlarged, fragmentary, perspective view of the pulp carrier and gripping device.

In the drawings, with special reference to Figs. 1 and 2, 10 and 11 represent the pressure rolls of the wet machine, each of which is suitably journaled within the housing 12 of the machine. The lower pressure roll 11 is driven in the customary manner by any suitable means, and about this roll passes the endless band or belt of fabric 13. The upper pressure roll 10, which is pressed in contact with the lower roll in the usual and well known manner, is mounted in suitable bearings carried by the housing 12 and is driven by means of its contact with the lower roll 11 and the fabric 13. The roll 10 takes from the belt 13 the pulp which has been deposited thereon and accumulates this pulp until, by successive layers, it has reached the predetermined thickness, when it is ready to be slit and removed from the roll.

A guide or track 14 is arranged in front of the pressure roll 10 and is carried by brackets 15 which are secured to the rods 110 16 of the machine at each side thereof. This track is preferably square-shaped, or

other polygonal cross section, and mounted to slide thereon, is a cutter carriage 17. A cutter arm 18 is pivotally connected at 19 to the carriage 17 and the cutter 20 is detachably secured to the inner end of this arm. This cutter is provided with a sharpened point 21 which is arranged to move in contact with the surface of the pressure roll 10 when it is moved across this roll by the carriage 17 to slit the sheet of pulp. The point 21 is so designed that it will not gouge into the material of the roll 10, but will smoothly move along its surface and in close contact therewith, so that the sheet 10 will be cut through its entire thickness. A stop 22 is provided on the carriage for limiting the motion of the arm 18 when the knife is being returned to its operative position, and an emergency stop 23 is also provided on the carriage for limiting the motion of the arm 18 should the cutter fail to function properly. The stop 23, however, is not in contact with the arm when the cutter is operating normally, and is simply provided as a safeguard for preventing the point of the cutter from catching on the end of the roll when it is starting on its forward movement, and also for preventing the possibility of the cutter catching or digging 25 into the roll should the track, for any reason, move away from the roll.

The cutter carriage 17 is moved back and forth by means of cords or ropes 24 and 25, which have their ends preferably passed 30 through and secured to the outer end of the cutter arm 18. The rope 25 passes over an idler 26 arranged at the right hand end of the track 14 (as viewed in Fig. 1); it is returned beneath the track where it is crossed, 35 and then passes over an idler 27. The rope 24 passes over an idler, like the idler 27, which is mounted upon the same shaft, but which does not show in the drawings. The outer ends of the ropes 24 and 25 are connected with the operating means of my device, described below.

As clearly seen in Fig. 1, the track 14 is arranged at an angle with the axis of the pressure roll 10. This angular arrangement 40 is provided so as to compensate for the continued rotation of the sheet of pulp as it is being slit by the cutter 20. The high end of the track is at the left of Fig. 1, and as the cutter moves from right to left it will be seen 45 that, if the sheet is to be cut squarely across, the cutter will have to travel upwardly as it advances to the cut. This is provided by the inclination of the track as shown in the drawings.

50 In order to imitate the hand operation of slitting the sheet of pulp, it is necessary that the slitting be done quickly; and, to accomplish this, I have provided a weight 28 which is vertically slidable upon ways or 55 tracks 29. The outer end of the rope 24

passes upwardly to the upper limit of travel of the weight 28, and is there passed over an idler 30. The end is brought downwardly and attached to the weight at 31. The outer end of the rope 25 is also attached to the weight 28 at 32. Mounted above the machine at an elevation governed by the width of the sheet of pulp to be cut, and the consequent, necessary travel of the weight 28, is the means for operating the weight of my device. These means comprise a bracket 33, supported by the ceiling above the machine or in any other suitable way. Journaled within the bracket 33 is a main shaft 34, which carries a gear 35. Below the shaft 34 is arranged a drive shaft 36, which carries at its outer end a pinion 37, meshing with the gear 35. The drive shaft 36 also carries a sprocket wheel 38, which is rotated by a sprocket chain 39, passing over a sprocket wheel 40. The sprocket wheel 40 is carried by an extension shaft 41, preferably attached to the outer end of the shaft of the lower pressure roll 11. Mounted so as to freely rotate upon the shaft 34 is a drum 42, and attached thereto at one of its ends is a belt or strap 43. The other end of this belt passes downwardly and is secured to the weight 28. As the drum is rotated in a clockwise direction, when viewed 45 from the right hand side of Fig. 1, the strap 43 will be wound upon its periphery and the weight 28 will be elevated. Passing through the drum 42 near its periphery, is a stop 44, the ends of which engage with the bracket 33 and limit the rotation of the drum, thereby preventing the lug 51 thereof from passing beyond the key 47. Endwise motion of the drum 42 upon its shaft is prevented by providing a set collar 45 at one 50 side thereof, and by an operating arm 46 at the opposite side thereof. This operating arm is rigidly attached to the shaft and is rotatable therewith. At its outer end is slidably carried a key 47 which is provided 55 with a downwardly extending arm 48 (Fig. 4). A cam 49 is carried by the bracket 33 and its surface is engageable with the arm 48 of the key 47. The key 47 is normally pressed inwardly by means of a spring 50 60 carried by the arm 46. The inner end of the key, in its innermost position, projects beyond the surface of the arm 46 and lies in a position where it will engage with a lug 51 provided on the drum 42. When the key 47 is in the position shown in the figures of the drawings and the arm is rotated, the drum 42 will also be rotated by the engagement of the key 47 with the lug 51 of the drum. When the drum 42 has 65 reached its predetermined point, the arm 48 of the key will engage with the cam 49 and move the key outwardly to a point where its engagement with the lug 51 will be released, whereupon the drum 42 will be 70

free to rotate, and gravity will cause the weight 28 to fall. As the drum is released before it has completed one entire revolution it will have time to return to the position shown in Fig. 1 before the arm with its key 47 has passed the point of engagement with the lug 51 of the drum, so that the drum will be almost immediately again engaged and rotated so as to raise the weight 28 for another movement of the cutter.

Attached to the outer end of the drive shaft 36 is a ratchet wheel 52, and engaging with this ratchet wheel is a ratchet pawl 53. The ratchet pawl is carried by the bracket 33 and its engagement with the ratchet wheel 52 will prevent the weight 28 from falling if, for any reason, the sprocket chain 39 should break, or anything else should fail to properly operate. It will be seen that if the weight 28 should accidentally fall before it has reached its predetermined upward motion, the sheet of pulp would not have reached its predetermined thickness and would be cut along a portion of its width. It will be obvious that as the weight 28 is being raised the cutter carriage 17 is being returned to the right hand side of the track as viewed in Fig. 1, and the apparatus is so timed that when it has reached this position the pulp will be at its predetermined thickness, at which time the weight will be released and draw the cutter across the roll through the sheet of pulp.

In order to take the flat sheets of pulp from the machine and place them in a stack, I provide a track 60 at each side of the machine. These tracks are inclined upwardly from the machine and mounted to move thereon is a pulp carrier 61. This pulp carrier is provided with gripping means for grasping the end of the sheet of pulp which comprise a stationarily arranged bar 62 and a movable bar 63, which extend the full width of the machine. The movable bar 63 is carried at the upper ends of arms 64. 65 are arms which are rigidly secured to the carrier 61, and which are arranged in spaced relation therewith. The arms 64 are pivotally attached near their middle portion to the lower ends of the arms 65, and are arranged between these arms and the carriers 61. Stops 66 are arranged at the inner ends of the tracks 60, and stops 67 at the outer ends of the tracks. The stops 66 are so arranged that when the carrier 61 is in the position shown in Fig. 2 the stops will engage the arms 64 above their pivotal connection and serve to move the bar 63 out of contact with the bar 62, thereby opening the jaws of the gripping means and permitting the edge of the sheet of pulp to pass therebetween, (see Fig. 2).

At this instant the carrier 61 is drawn upwardly by means hereinafter described,

thus allowing the movable bar 63 to fall into contact with the stationary bar 62, which will cause the sheet to be frictionally held between the bars 63 and 62 by reason of the weight of the bar 63 and its attaching arms. As the carriage reaches the upper point of its travel the arms 64 will engage with the stops 67 below their pivotal points, which will serve to open the gripping means and allow the sheet of pulp to fall in between the tracks and to be stacked in a pile as shown at 68 in Fig. 2.

The pulp carrier is operated by ropes 69 and 70, one arranged at each side of the carrier. The ropes pass rearwardly and over idlers 71. The rope 69 passes upwardly and connects directly with the drum 72, while rope 70 is preferably passed over idlers 73 and also around the drum 72. The drum 72 is mounted upon a shaft 74, which is mounted in suitable journals. A drum 75 of smaller diameter than the drum 72 is also mounted upon the shaft 74 and is connected with a drum segment 76 by a belt or rope 77.

The drum segment 76 is loosely mounted upon the outer extended end of the shaft 34 and prevented from moving endwise thereon by means of a set collar 78 and an operating arm 79. The drum segment 76 is preferably made adjustable so that it may be adapted to pressure rolls of different sizes, or adjusted when the pressure roll is reduced in diameter by having its surface redressed, it being obvious that the rate of travel of the pulp carrier 61 must be the same as the rate of discharge of the sheet of pulp. A stop 84 is preferably provided for the drum segment so as to limit its travel, counter-clockwise, beyond the position shown in Fig. 2.

The operating arm 79 carries a key 80, similar in design to key 47, and having an upwardly extending arm 81. A cam 82, like the cam 49, is supported by an extension 83 of the bracket 33. This cam serves to move the key 80 out of engagement with the drum segment 76, when it has moved the pulp carrier 61 to the upper limit of its travel. The track 60 being inclined, as hereinbefore stated, the weight of the pulp carrier will be sufficient to return the device to the position shown in Fig. 2 by gravity.

From the foregoing description it will be evident that when the sheet of pulp has reached its predetermined thickness, the weight 28 will have been drawn upwardly to its uppermost position by the drum 42, and the cutter carriage 17 with the cutter 20 will have been moved to the right hand side of the track as viewed in Fig. 1, whereupon the drum 42 will be released, the weight will fall, and through the medium of the cords 24 and 25, the carriage 17 will quickly draw the cutter 20 across the face

of the pressure roll 10 and slit the sheet of pulp thereon. The lower edge of the sheet of pulp will fall by gravity and move downwardly, as it is being discharged from the machine, to a position between the open jaws of the gripping device. When the edge is moved between these jaws the apparatus is so timed as to cause the drum segment 76 to operate and draw the carrier 10 61 upwardly on its tracks. As the carrier starts to travel the arms 64 will be released from engagement with the stops 66, thereby closing the gripping means on the edge of the sheet of pulp. As the carrier continues 15 its travel along the tracks 60 the outer edge of the pulp sheet will be moved along between the tracks 60, as the sheet is being discharged from the machine, thereby keeping the sheets substantially flat. When the 20 upper predetermined travel of the carrier is reached the jaws thereof will be released and the sheet allowed to fall in between the tracks on the pile 68.

Obviously, some modifications of the 25 details herein shown and described may be made without departing from the spirit of my invention or the scope of the appended claims; I do not, therefore, wish to be limited to the exact embodiment herein shown 30 and described.

Having thus described my invention, what I claim is:

1. In a wet machine, a roll adapted to accumulate a deposit thereon, a cutter movable across the roll, means for forcing the cutter toward the roll during the cutting stroke, and means for retracting the cutter from the roll during the return stroke.

2. In a wet machine, a roll adapted to 40 accumulate a deposit thereon, a cutter movable across the roll, a weight for quickly moving the cutter across the roll to slit the sheet of pulp, and means for slowly elevating the weight to its initial position and 45 slowly moving the cutter back to its initial position.

3. In a wet machine, a roll adapted to 50 accumulate a deposit thereon, means for slitting the accumulated pulp while the roll is rotating comprising a track disposed in front of the roll and arranged at an acute angle with the axis thereof, a cutter movable on the track and engageable with the surface of the roll, and means for operating 55 the cutter back and forth across the surface of the roll, the initial position of the cutter being at the lower end of the track, whereby the sheet of pulp is cut substantially at right-angles with its side faces.

4. In a wet machine, a roll adapted to 60 accumulate a deposit thereon, a cutter movable across the roll, a vertically reciprocating weight connected with the cutter, and means for periodically tripping the weight.

5. In a wet machine, a roll adapted to ac-

cumulate a deposit thereon, a cutter movable across the roll, a vertically reciprocating weight connected with the cutter, means for periodically tripping the weight, and means for preventing the weight from falling before it is tripped. 70

6. In a wet machine, a roll adapted to accumulate a deposit thereon, a cutter movable across the roll, a vertically reciprocating weight connected with the cutter, a drum for elevating the weight, means for rotating the drum, and means for periodically releasing the drum, whereby the weight is allowed to fall. 75

7. In a wet machine, a roll adapted to 80 accumulate a deposit thereon, a cutter movable across the roll, a vertically reciprocating weight connected with the cutter, a drum for elevating the weight, means for rotating the drum, and cam actuated means 85 for periodically releasing the drum, whereby the weight is allowed to fall.

8. In a wet machine, a roll adapted to accumulate a deposit thereon, a cutter movable across the roll, actuating means for the 90 cutter, an operating arm, connecting means between the arm and the actuating means, means for operating the latter, and cam means for releasing the connecting means at a predetermined point, thereby allowing the 95 actuating means to operate.

9. In a wet machine, a roll adapted to accumulate a deposit thereon, a cutter movable across the roll, a vertically reciprocating weight connected with the cutter, elevating means for the weight, an operating arm, connecting means between the arm and the elevating means, means for operating the latter, and cam means for releasing the connecting means at a predetermined point, 100 thereby allowing the weight to fall. 105

10. In a wet machine, a roll adapted to accumulate a deposit thereon, a cutter movable across the roll, a vertically reciprocating weight connected with the cutter, a rotatably mounted drum, means connecting the drum and the weight, an operating arm adjacent to the drum, a key carried by the arm and normally engageable with the drum to rotate the same, and a cam engageable with the key to release its engagement with the drum, thereby allowing the weight to fall. 110 115

11. In a wet machine, means for receiving and piling the sheets of pulp, formed thereon, comprising a pulp carrier mounted in front of the machine, gripping means carried by the carrier, actuating means for the carrier, an operating arm, means for normally connecting the actuating means and 120 the arm, and means for periodically disengaging such actuating means and arm, thereby allowing the carrier to return to its inoperative position.

12. In a wet machine, means for receiving 130

and piling the sheets of pulp, formed thereon, comprising a pulp carrier mounted in front of the machine, gripping means carried by the carrier, means for operating the carrier, comprising a drum segment, an operating arm, means for normally connecting the segment and arm, and means for periodically disengaging such segment and arm, thereby allowing the carrier to return to its 10 inoperative position.

13. In a wet machine, means for receiving and piling the sheets of pulp, formed there-

on, comprising a pulp carrier mounted in front of the machine, gripping means carried by the carrier, actuating means for the 15 carrier, an operating arm, a key carried by the arm and held normally in engagement with the actuating means, and cam means for periodically disengaging the key from the actuating means, thereby allowing the 20 carrier to return to its inoperative position.

In testimony whereof, I have hereunto signed my name.

HENRY A. CONSTANTINE.
